United States Patent

Des. 235,530
Patented June 24, 1975

235,530

BOAT

David T. Livingston, Seattle, Wash., assignor to Reinell
Boats, Inc., Marysville, Wash.

Filed Aug. 24, 1973, Ser. No. 391,226

Term of patent 14 years

Int. Cl. D12—06

U.S. Cl. D12—62

FIG. 1

FIG. 2

FIG. 3

FIG. 4

FIG. 5

FIG. 1 is a top view of the novel boat design of this invention;

FIG. 2 is a side elevation of the boat of FIG. 1;

FIG. 3 is a perspective view of the boat of FIG. 1;

FIG. 4 is a front elevation thereof; and

FIG. 5 is a rear elevation thereof.

I claim:

The ornamental design for a boat, as shown and described.
